UNITED STATES PATENT OFFICE.

JOHN G. REBER, OF CHICAGO, ILLINOIS; OLIVE S. REBER, ADMINISTRATRIX OF SAID JOHN C. REBER, DECEASED, ASSIGNOR TO THE SEFTON MANUFACTURING COMPANY, OF CHICAGO, ILLINOIS, A CORPORATION OF INDIANA.

FOLDING BOX.

1,003,510.

Specification of Letters Patent. Patented Sept. 19, 1911.

Application filed October 21, 1908. Serial No. 458,796.

To all whom it may concern:

Be it known that I, JOHN G. REBER, a citizen of the United States, residing at Chicago, in the county of Cook and State of Illinois, have invented certain new and useful Improvements in Folding Boxes, of which the following is a specification.

My invention relates to folding boxes made of paper board or the like, and the 10 general object thereof is to provide a simple and efficient box of this character, possessing features of advantage and utility which will be apparent from the description hereinafter given.

15 My present invention is an improvement upon that described and claimed in an application for patent filed by me on March 19, 1906, Serial No. 306,854, in which form of box I employed flexible strips of wood 20 or the like at the top edges of two of the opposite sides for the purpose of not only strengthening such sides but also of holding the box in its erect or assembled condition. My present invention pertains more 25 particularly to the means for and manner of holding or securing these strips to the box and also relates to certain features of box construction to coöperate with said strips.

30 In the drawings, Figure 1 is a plan view of a blank from which the particular box herein illustrated, known as a suit box, is formed; Fig. 2 a perspective of one corner of the box showing method of folding;

35 Fig. 3 an enlarged sectional elevation on the line 3—3 of Fig. 4; Fig. 4 a perspective of the box in its assembled or erect form; Fig. 5 a perspective of one end of the box with its flexible strip removed; Fig. 6 a section on the line 6—6 of Fig. 3; Fig. 7 an elevation of a portion of one end of the box; Fig. 8 a plan view of one end of a blank of modified form; Fig. 9 a perspective of one end of a box made from the modified 40 form of blank illustrated in Fig. 8; Fig. 10 a section on the line 10—10 of Fig. 9; and Fig. 11 a perspective on a somewhat larger scale than in Fig. 9 illustrating one end of such modified form of box but with its 45 flexible strip removed.

50 My invention is applicable to different forms and types of boxes, such as hat boxes, suit boxes and the like and, although in the

present instance I have shown my invention in connection with the particular form 55 or type of box known as a suit box, yet it will be understood that I do not intend to limit myself to such special form of box, particularly as the proportions of the box may be obviously changed to produce a 60 great variety of boxes intended for different special purposes.

Referring to the present embodiment of my invention, which is in the form of the well-known suit box, the blank from which 65 such box is formed comprises a rectangular bottom A, two opposite side walls B, two end walls C C, all of which are hinged to the bottom A, and also corner folds D and E. These corner folds are substantially triangular, the same being arranged in four pairs at the four corners of the box, of which the folds D are hinged to the ends of the side walls B and of which folds E are hinged to the ends of the end walls C, 70 such folds being hinged on the diagonal score line e. For a purpose hereinafter explained and made apparent during the explanation of the setting up or assembling 75 of the box, each of the corner folds D is provided along its outer edge with a triangular shaped recess d. By reason of the fact that the walls B are longer than the walls C, and as a matter of convenience in 80 description, I prefer to call the former the side walls and the latter the end walls, although they all may be considered side 85 walls.

To the outer edges of the end walls C of the box are hinged extensions or flaps which 90 are hinged upon each other and adapted to be folded over upon or wrapped around strips F of flexible material, such as thin strips of wood or wood veneer, such folding being done in the particular manner hereinafter explained. As shown the innermost flaps or extensions c are continuous or entire but by preference, the outermost ones only of these flaps are severed, the same being transversely cut along the two lines c², so 100 as to form the end portions c' and the central or intermediate portions or extensions c³. As shown in Fig. 1, the lines c² are oblique for the purpose of cutting the outer corners of the flaps c³ on a bias, thereby 105 forming on the inner adjacent corners of

the extensions c' the tongues or points c^4 , having the office or function hereinafter explained.

In practice, the strips F which are flexible and afford a torsional strain or pressure when twisted, are folded or wrapped within the extensions or flaps, the extensions c' being tucked behind the strips with their outer faces lying against the inner faces of the 10 end walls of the box. The intermediate or short flaps c^3 are merely folded over the strips and positioned flat against the inner faces of the end walls of the box as shown in Fig. 4, instead of being folded underneath 15 and around the strips, as is the case with the extensions c' . The intermediate extensions are secured to the end walls of the box in any suitable manner, as for instance by means of a staple G passing through such 20 end walls and through the extensions c^3 , as clearly indicated in Fig. 4.

The box as thus far described represents the construction as produced at the factory, the box being shipped to the customer or 25 user in the flat form with the side walls B and corner folds folded inwardly and resting flat upon the bottom of the box and upon the end walls, the corner folds E being at this time positioned underneath and held 30 by the flexible strips applied to the box in the manner explained. When it is desired by the customer or user to put the box to use the same is brought to erect form by merely raising the end walls and folding them together 35 toward each other and then lifting and slightly twisting the ends of the strips in order to permit such strips to slip over the upper edges of the corner folds and to take their position on the inner sides or faces 40 thereof. In this lifting of the strips, the latter are twisted, but owing to the fact that they are flexible and resilient, the same spring back into normal condition after they have been slipped over the upper edges of 45 the corner folds to thereby lock and maintain the box in erect form.

By dividing the outermost flaps or extensions in the manner described the strips are held in proper relationship with the end 50 walls by means of the intermediate or central extensions, but at the same time are permitted to properly yield or twist even beyond their middle portions, in the operation of applying them over the corner folds. It 55 will be understood that the tongues c^4 extend underneath the strips within the lines of the central or intermediate extensions c^3 , with the result that the extensions thus wrapped around the strips are locked in 60 place so that in the lifting or twisting of the strips it is impossible to detach such extensions from the strips. In this simple manner the extensions and strips are held together and at the same time the cutting of 65 the free corners does not detract from the

efficiency of the central extensions but rather improves the appearance thereof. The object of the notches d in the corner folds D is for the purpose of assembling and locking the box in erect condition without requiring the strips to be raised as far back as would otherwise be necessary. It will be understood that the score lines running longitudinally through the central extensions c^3 are not essential but are incidental to the formation of the score lines which divide the extensions c' and on which they are hinged.

My invention may be applied to boxes made from different forms of blanks without departing from the spirit of my invention. For instance, while in the box just described both the corner folds D and E were hinged to the walls of the box, yet if desired only one member of each pair of corner folds 85 may be so hinged. Such a modified form of box is illustrated in Figs. 8 to 11, wherein the parts similar to those illustrated in the other figures are provided with the same letters of reference but primed.

As illustrated in Fig. 8 the blank comprises the bottom A', the side walls B' B', and the end walls C', of which only one is shown. Each corner of the box is provided with the corner folds D' E' hinged on the diagonal line e' , of which the corner folds D' are hinged to the ends of the side walls B'. However, in this particular instance the corner folds E' are not hinged to the end walls but are separated therefrom by the cut e^2 . Moreover, in this modified form the corner folds E', instead of being triangular as in the form hereinbefore described, are trapezoidal in shape, the same being extended as far as the outer line of the extensions of the end walls. As in the form first described, this modified form is provided with end wall extensions c^5 , c^6 , but in this particular instance both extensions are cut and moreover on straight lines c^7 , thereby forming the end portions or extensions proper marked c^5 , c^6 and the central or intermediate portions or extensions c^8 .

In practice the corner folds E' are brought inwardly with their outer faces resting flat upon the inner faces of the end walls and after the strips have been applied to the flaps or extensions in the same manner as previously described, the corner folds E' are secured to the end walls in suitable manner and in the present instance the parts are so secured by the same staples or fasteners H which are employed to fasten the central extensions c^8 in place, all as clearly indicated in Fig. 9. It is obvious that the central extensions c^8 need not be divided by the longitudinal score line which is present as an incident in actual practice to the formation of the score line on which the extensions c^5 , c^6 are hinged. Likewise the folds E' have two 130

score lines which are unnecessary but merely incidental in the passing of the blank through a machine for the formation of the extensions c^5 , c^6 .

5 The box is shipped from the factory in collapsed or flat form, with the side walls resting flat upon the bottom of the box and with the corner folds D' folded down upon the corner folds E' . The box is set up or 10 assembled to its erect form in the same manner as the first form of box described.

It will be understood that where my invention is applied to a suit box, where the top and bottom portions are similar, another 15 box portion of the same character is provided but differing slightly in size so that one portion may be readily telescoped into the other as is the case in the conventional form of suit boxes. Also where my invention 20 is applied to another form of box such as a hat box any suitable lid or cover, of the same structure as the body portion or otherwise, may be provided.

I claim:

25 1. A folding box comprising a bottom, walls hinged thereto, corner folds connected with two opposite walls and foldable into the box, flexible strips for the upper edges of the end walls, and separate extensions on 30 each of said end walls, which extensions are wrapped around the strips; substantially as described.

2. A folding box comprising a bottom, walls hinged thereto, corner folds connected

with two opposite walls and foldable into 35 the box, flexible strips for the upper edges of the end walls, and extensions on said end walls, which extensions are wrapped around the strips and extended inwardly on their adjacent edges; substantially as described. 40

3. A folding box comprising a bottom, walls hinged thereto, corner folds connected with two opposite walls and foldable into the box, flexible strips for the upper edges 45 of the end walls, and extensions on said end walls, the outermost one of which extensions is transversely cut in two places, forming two end portions which are wrapped around the strip and an intermediate portion which extends over such strip and is secured to its 50 end wall; substantially as described.

4. A folding box comprising a bottom, walls hinged thereto, corner folds connected with two opposite walls and foldable into the box, flexible strips for the upper edges 55 of the end walls, and extensions on said end walls, the outermost one of which extensions is transversely cut in two places, forming two end portions which are wrapped around the strip and an intermediate portion which extends over such strip and is secured to its end wall, said end portions being extended inwardly on their adjacent edges; substantially as described. 60
